UNITED STATES PATENT OFFICE.

GEORGE EDWARD SANFORD, OF OAK PARK, ILLINOIS, ASSIGNOR, BY MESNE ASSIGNMENTS, TO SANFORD CLARIFYING AND SEPARATING COMPANY, A CORPORATION OF DELAWARE.

CENTRIFUGAL SEPARATOR.

1,161,981.

Specification of Letters Patent. Patented Nov. 30, 1915.

Application filed February 27, 1911. Serial No. 611,134.

To all whom it may concern:

Be it known that I, GEORGE E. SANFORD, a citizen of the United States, residing at 147 North Humphrey avenue, in the city of Oak Park, in the county of Cook and State of Illinois, have invented certain new and useful Improvements in Centrifugal Separators, of which the following is a specification.

My invention relates to centrifugal separators or machines for clarifying liquids by separating all solid matter therefrom, or for separating heavier liquids from lighter ones with which they may be commingled, by centrifugal force.

15 The object of the invention is to generally improve the construction of machines of this class for the purposes, 1, to generally increase their efficiency; 2, to simplify their construction; 3, to add to their durability; 23 4, permit of the easy and economical removal and replacement of parts; and 5, to permit of thorough cleaning without the necessity of removing any parts.

With these, and other objects in view, 25 my invention consists in the improved construction, arrangement and combination of the parts of a machine of this class, all as hereinafter fully described and afterward specifically pointed out in the appended 30 claims.

In order that those skilled in the art may be enabled to make and use my invention, I will now proceed to fully and specifically describe the preferred embodiment 35 thereof as illustrated in the accompanying drawings, in which—

Figure 1, represents a view in central vertical longitudinal section of my improved separator, mounted upon a suitable turbine 40 for driving it, the turbine being shown in side elevation. Fig. 2, represents a top plan view of the separator, partly broken away. Fig. 3, represents a sectional view taken on the horizontal plane on the line 3—3 of Fig. 45 1, looking downward. Fig. 4, represents a view similar to that of Fig. 3 on the plane on the line 4—4 of Fig. 1 also looking downward.

Like reference characters mark the same 50 parts wherever they occur in the several figures of the drawings.

Referring specifically to the drawings, 55 indicates the casing of a turbine or other motor suitable for a separator, the same being provided with a vertical shaft 11 upon

which the separator is mounted and with which the separator is revolved horizontally, in the usual manner of machines of this class. Upon the top 12 of the casing 10 of the turbine, around the shaft 11, is 60 mounted a sleeve 13, the upper end 14 of the shaft 11 being decreased in diameter, leaving an annular shoulder 15 upon which is mounted the central flat top or apex 16 of a metallic cone 17 which, at its lower end, or 65 periphery is curved to substantially the horizontal, as at 18. The reduced upper end 14 of the turbine shaft 11 is threaded and a nut 19 on this part securely holds the cone 17 in position.

Rigidly secured above the cone 17 is a frustum 20 of a different pitch from that of the cone so that there is formed between the two cones a chamber 21 of gradually decreasing width from top to bottom. The 75 open top or mouth 22 of said chamber 21 is much greater in diameter than the apex of the cone 17. The lower edge of the frustum 20 terminates a short distance above the curve of the portion 18 of the cone 17, leaving an annular space or opening 23 to be later referred to. Projecting slightly within the mouth 22 of the cone 20 is a vertical pipe 24 through which the liquid to be clarified, or separated into its constituent parts, 80 85 is discharged into the separator.

Radiating in downwardly inclined directions from the top 12 of the casing of the turbine, are ribs 25 which are secured at their ends to, or formed integral with the inner 90 flange 26 of a reversed annular channel bar 27, to the outer flange 28 of which is secured the outer wall 29 of the bowl of the separator, the said wall being of cylindrical form and supporting on its top an inwardly and 95 slightly downwardly extending annular plate 30. The ribs 25 and the annular plate 27 form the bottom of the bowl while at the top there is mounted below and partially under the annular plate 30, an annular plate 100 105 which I denominate the "skimming disk" there being a space 35' between the plate 30 and the skimming disk 35, the purpose of which will be stated hereafter.

A trough 36 is secured upon the outside of 105 the upper portion of a cylinder 37 which forms the outer casing of the whole separator including the turbine, said trough having at its upper end an outwardly and downwardly inclined cover 38 which partially pro- 110

jects over the cylinder 37, and from the upper edge of the cylinder 37 there projects outwardly and downwardly an annular plate 39, into the trough 36. In one side or more 5 of the cylinder 37 is an opening 40, and outside of this opening, whether one or more, is a discharge pipe 41, the lower side of which is on a level with plate 34, of the bottom of the trough, said discharge pipe being inclined downward in order to discharge the 10 material which passes through it into any suitably placed receptacle.

Secured upon the top of the annular channel bar 27 and to the inside of the outer wall 15 29 of the bowl separator are radial vertical plates or partitions 44 whose upper inner corners are cut away so as to form rests 45 for the skimming disk 35, said plates dividing the space between the periphery of the 20 bowl and the outlet into compartments in which the liquid will be practically at rest and in which the impurities will be deposited and be retained while the liquid escapes through the opening 35'.

25 It will be observed that the bowl is open at the top and at the bottom. The cone 17 forms a cover for the opening in the bottom with said cover spaced from the bottom. As the liquid to be clarified is introduced into the bowl 29 through the supply pipe 24, the liquid falls on the lower cone 17. The bowl being in rapid rotation, the liquid is thrown outward by the centrifugal force against the cone 20 and is carried 30 down and discharged through the opening 23 through which the discharged liquid flows outwardly against the periphery of the bowl 29 where it will accumulate until it forms a cylinder of liquid. The inner 35 surface of the cylinder of liquid will be parallel with the axis of the bowl and on a line with the opening in the top of the bowl. The heavier parts, such as mud, etc., contained in the liquid to be clarified will be 40 thus carried to the periphery of the bowl and be deposited and retained in the compartments formed by the annular plate 27, the top of the bowl 30, the periphery of the bowl 29 and the plates 44. The lighter 45 impurities will gather on the inner surface of the cylinder of liquid nearest the axis of the bowl. By virtue of the cone 17 being centered over the opening in the bottom of the bowl and spaced therefrom and having 50 its lower edge flared outwardly, and the frustum 20 being centered over the cone and spaced therefrom and also spaced from the skimming disk, the cone and frustum coöperate to form an open ended compartment 55 21 and prevent the liquid from splashing against the contents between the frustum and the periphery of the bowl, thereby causing the liquid to be subjected to an efficient centrifugal action. As the centrifugal 60 force forms the liquid into a cylindrical 65

body with its inner surface parallel with the axis of the bowl, as stated, the surplus liquid, as it accumulates, will escape from the upper opening because this upper or top opening is farthest from the axis, it being 70 larger than the bottom opening. By thus making the top opening larger than the bottom opening the discharge will be through the top opening when the bowl rotates. The clarified liquid will be forced upward and 75 through the space between the annular cover of the bowl and the skimming disk 35, when it will again rise and pass over the annular cover of the bowl and be turned outward by centrifugal force into trough 80 36, from which it will be discharged through an outlet or pipe 43.

While the bowl is rotating, the contents thereof are carried around with it, the radial plates 44, extending into the contents 85 of the bowl, preventing the rotation of the bowl without the simultaneous rotation of the contents thereof, which would occur to some extent in the absence of such radial partition, generating currents and eddies 90 which would disturb the impurities and prevent them from being deposited and retained.

When the bowl stops rotating, all substances remaining in it will be discharged 95 through the openings in the bottom of the bowl under the cone 17. The solid matter which is deposited in the compartments formed by the plates 44 can be scraped down by reaching through the opening in 100 the top 30 and the skimming disk 35 and the space, allowed for that purpose, between the skimming disk 35 and the cone 20.

While I have specifically described the exact construction of the various parts of 105 my improved separator, it will be obvious to those skilled in the art that the invention does not depend entirely upon such specific construction and it will be readily understood that many slight changes and variations might be made in the form and material in the various component parts, without departing from the spirit and scope of the invention.

Having thus described my invention, what 115 I claim as new and desire to secure by Letters Patent of the United States is:

1. A centrifugal separator comprising a bowl whose annular side wall is imperforate and which is provided with a discharge opening in its bottom and at its top also provided with an opening large enough to permit cleaning of the bowl, a cone having a flared lower end centered over the opening in the bottom of the bowl and spaced therefrom, and a frustum centered and spaced over the flared edge of the cone.

2. A centrifugal separator comprising a bowl provided with a large opening in its top and having its bottom provided with an 130

- opening, a skimming disk of larger diameter than the opening in the top and mounted below the opening in the top to provide a space between it and the top, the skimming disk having an opening smaller in diameter than the diameter of the opening at the top of the bowl and through which liquid is conveyed to the bowl, the opening in the bottom of the bowl being of less area than the opening in the top of the bowl whereby as the bowl rotates liquid will accumulate on the periphery of the bowl incident to centrifugal force and be discharged around and above said skimming disk directly through the opening in the top of the bowl.
5. A centrifugal separator comprising a bowl provided with a large discharge opening in the bottom and also with a large discharge opening in its top, a cone centered in the bowl above the opening in the bottom, a frustum centered above the cone at a distance therefrom and having an opening in its apex which has a more acute pitch than the cone, and a skimming disk centered and spaced above said frustum whereby as the bowl rotates the liquid entering the frustum will be carried to the periphery of the bowl and upward and around said disk and discharged through said top opening of the bowl.
10. A centrifugal separator comprising a bowl, provided with a large opening in its bottom, and also provided with an opening in its top which is larger than the opening in the bottom, a cone centered in the bowl and spaced over said opening in the bottom of the bowl, a frustum centered and spaced over the cone and means for rotating the bowl, the opening in the top of the bowl serving as a discharge outlet when the bowl is rotated and the opening in the bottom of the bowl serving as a discharge outlet when the bowl is stationary.
15. A centrifugal separator comprising a rotatable bowl provided with a large opening in its top and a large opening in its bottom, a cone centered and spaced over the bottom opening, a frustum centered over the cone in spaced relation to the latter, and being of more acute pitch than the cone, the cone and frustum being carried by the bowl and arranged to distribute the liquid which is introduced into the bowl through the opening in the top of the bowl around the periphery of the bowl at the bottom thereof.
20. A centrifugal separator comprising a bowl provided with a large opening in its top and a large opening in its bottom, a cone centered and spaced over the bottom opening, a frustum centered over the cone in spaced relation to the latter, the frustum being of more acute pitch than the cone, the cone and frustum being arranged to distribute the liquid which is introduced into the bowl through the opening in the top of the bowl.
25. A centrifugal separator comprising a bowl around the periphery of the bowl at the bottom thereof, the opening in the top of the bowl being of greater diameter than the opening in the bottom, whereby, the contents are discharged upward through the opening in the top of the bowl during rotation of the latter.
30. A centrifugal separator comprising a bowl provided with a large opening in its top and with a large opening in its bottom, a cone centered over the opening in the bottom to prevent liquid introduced through the opening in the top from falling through the opening in the bottom during rotation of the bowl and permitting discharge of the contents of the bowl through the bottom opening when the bowl ceases to rotate.
35. A centrifugal separator comprising a bowl whose shell is imperforate and which bowl is provided with a discharge opening in its top and with an opening in its bottom the upper opening being of greater diameter than the lower opening, a cone disposed over the opening in the bottom and whose lower edge terminates above the plane of the bottom of the bowl, a frustum disposed beneath the opening in the top and centered and spaced above the cone to provide a chamber between them.
40. A centrifugal separator comprising a bowl provided with an opening in its top and with an opening in its bottom, a skimming disk of larger diameter than the opening in the top disposed within the bowl and centered below the opening in the top, the skimming disk having a central circular opening of smaller diameter than the opening in the top of the bowl, a cone centered over the opening in the bottom of the bowl and spaced therefrom, and a frustum centered over the cone and spaced therefrom.
45. A centrifugal separator comprising a bowl provided with a large opening in its top, a skimming disk of larger diameter than the opening in the top which is centered within the bowl and spaced from the opening in the top, said disk having a circular opening in its center of smaller diameter than the opening in the top of the bowl, a cone disposed within the bowl below the skimming disk and centered with relation to the opening in the latter, and a frustum centered within the bowl in spaced relation to the cone.
50. A centrifugal separator comprising a bowl provided with a large opening in its top and an opening in its bottom, radial vertical plates secured to the interior of the bowl and forming compartments to retain scums, a skimming disk of larger diameter than the opening in the top of the bowl which is disposed within the bowl and centered and spaced below the opening in the top of the bowl, a cone mounted within the bowl and spaced below the opening in the

top of the bowl, and a frustum disposed within the bowl and centered and spaced from the cone.

12. A centrifugal separator comprising a bowl, a vertical shaft on which the bowl is mounted, a channel plate secured to the shell of the bowl at the bottom thereof and forming a portion of the bottom of the bowl, the remaining portion of the bottom of the bowl being open, a covering member connected to the shaft and disposed over the open portion of the bottom of the bowl, and ribs secured at their inner ends to said cover member and at their outer ends to the inner side of said channel plate, said cover member resting on said ribs.

13. A centrifugal separator comprising a rotatable bowl provided with an opening in its top and with an opening in its bottom, means for rotating the bowl, means for supplying liquid to the bowl through the opening in the top thereof, and means including a cone and a frustum disposed within the bowl and spaced from the bottom to receive the supply of liquid delivered to the bowl and adapted to deflect the liquid outwardly to the periphery of the bowl and prevent discharge of the liquid through the bottom opening in the bowl during rotation of the bowl and permitting discharge of the liquid through the bottom opening when the bowl ceases to rotate.

14. A centrifugal separator comprising a rotatable bowl provided with an opening in its top and with an opening in its bottom, means for rotating the bowl, means for supplying liquid to the bowl through the opening in the top thereof, and a cone and a frustum disposed within the bowl and spaced from the bottom thereof to receive the supply of liquid delivered to the bowl and adapted to deflect the liquid outwardly to the periphery of the bowl, radial spaced plates in the bowl forming compartments to cause the liquid thrown to the periphery of the bowl to rotate as fast as the rotation of the bowl, a skimming disk supported on said radial plates and spaced from the opening in the top of the bowl and around and over which skimming disk the liquid is thrown by the centrifugal force developed incident to rotation of the bowl and out through the opening in the top of the bowl.

15. A centrifugal separator comprising a rotatable bowl provided with an opening in its top and with an opening in its bottom, means for rotating the bowl, means for supplying liquid to the bowl through the opening in the top thereof, and a cone and a frustum disposed within the bowl and spaced from the bottom of the bowl to receive the supply of liquid delivered to the bowl and adapted to deflect the liquid outwardly to the periphery of the bowl, radial spaced plates in the bowl forming compartments to

cause the liquid thrown to the periphery of the bowl to rotate as fast as the rotation of the bowl, a skimming disk supported on said radial plates and spaced from the opening in the top of the bowl and around and over which skimming disk the liquid is thrown by the centrifugal force developed incident to rotation of the bowl and out through the opening in the top of the bowl, and a trough arranged to receive the clarified liquid discharged through the opening in the top of the bowl.

16. A centrifugal separator comprising a rotatable bowl provided with a discharge opening in its top and with a discharge opening in its bottom, said openings being arranged in alinement, the top opening being of larger diameter than the bottom opening, means for rotating the bowl, a cone and a frustum constructed and arranged within the bowl and spaced from the bottom thereof and rotatable with the bowl to distribute the liquid in the bottom of the bowl and deflect it toward the periphery of the latter.

17. A centrifugal separator comprising a bowl provided with an opening in its bottom and also provided with an opening in its top which is larger than the opening in the bottom, a cone and a frustum disposed within the bowl and spaced from the bottom of the bowl, and a skimming device arranged below the opening in the top of the bowl and having an opening therein which is smaller than the opening in the top of the bowl.

18. A centrifugal separator comprising a bowl provided with an opening in its bottom and also provided with an opening in its top which is larger than the opening in the bottom, a cone and a frustum disposed within the bowl and spaced from the bottom of the bowl, a skimming device arranged below the opening in the top of the bowl and having an opening therein which is smaller than the opening in the top of the bowl, and radial vertical plates secured to the interior of the bowl to form compartments and on which plates said skimming disk is supported.

19. A centrifugal separator comprising a bowl provided with an opening in its top and with an opening in its bottom, the top opening being larger than the bottom opening, a skimming disk of larger diameter than the opening in the top disposed within the bowl and centered below the opening in the top and having a central circular opening of smaller diameter than the opening in the top of the bowl, a cone centered over the opening in the bottom of the bowl and spaced therefrom and having its lower edge flared outwardly, and a frustum centered over the cone and spaced therefrom and also spaced from the skimming disk and adapted with the cone to form an open-ended com-

partment and to prevent the liquid from splashing against the contents between the frustum and the periphery of the bowl and thereby causing the liquid to be subjected to an efficient centrifugal action.

20. A centrifugal separator comprising a bowl provided with a discharge opening at its top, a skimming disk of larger diameter than the opening in the top and which is 10 centered in the bowl and spaced below said opening in the top, said disk having a circular opening in its center of smaller diameter than the opening in the top of the bowl, the bowl also having a large opening in the 15 top and which is larger than the opening in the skimming disk, a cone disposed within the bowl below the skimming disk and cen-

tered with relation to the opening in the latter, a frustum centered within the bowl in spaced relation to the cone, and radial vertical plates within the bowl between the annular wall thereof and said cone and frustum adapted to prevent the lighter impurities separated from the liquid from becoming mixed with the clarified liquid which 25 passes through the discharge opening in the top of the bowl.

In testimony whereof I have affixed my signature in presence of two witnesses.

GEORGE EDWARD SANFORD.
